DESIGN FOR AN OVEN CONTROL KNOB
FOR GAS STOVESRichard I. Felver, Pittsburgh, Pa., assignor to
Standard Gas Equipment Corporation, Balti-
more, Md., a corporation of Maryland

Application October 22, 1946, Serial No. 134,176

Term of patent 14 years

(Cl. D81—25)

To all whom it may concern:

Be it known that I, Richard I. Felver, a citizen of the United States, residing at Pittsburgh, county of Allegheny, State of Pennsylvania, have invented a new, original, and ornamental Design for an Oven Control Knob for Gas Stoves, of which the following is a specification, reference being had to the accompanying drawing, forming part thereof.

Figure 1 is a face view of an oven control knob for gas stoves showing my new design.

Figure 2 is an edge view partly in cross section to show the face contour.

Figure 3 is a face view with the knob rotated to an "on" position.

I claim:
The ornamental design for an oven control knob for gas stoves, as shown.

RICHARD I. FELVER.
